SCYTHE SNATH

Ernest N. Birge, Seymour, Ind., assignor to
Seymour Manufacturing Company, Incorporated,
a corporation of Delaware

Application September 22, 1939, Serial No. 296,025

7 Claims. (Cl. 306—1.3)

5 This invention relates to scythes and is especially concerned with the metallic fitting which is usually secured to the end of the snath or handle to afford means for attaching the scythe blade to the snath. One object of the invention is to provide a fitting which includes means for adjusting the plane of the scythe blade with respect to the axis of the snath so that the inclination of the blade may be varied to suit the individual user.

10 Another object is to include the usual means for adjusting the blade in its own plane to vary the angle of the cutting edge with respect to the snath axis. And it is also an object of the invention to provide means for tilting the blade bodily in a direction transverse to its own plane with the effect of adjusting the blade through a limited angle about the axis of the snath or an axis adjacent thereto. It is also an object of the invention to provide a construction affording 15 these various adjustments which shall be comparatively simple and economical to manufacture, and in which the adjustments can be effected by the user without any special skill. The invention consists of certain features and elements 20 of construction in combination, as herein shown and described and as indicated by the claims.

25

In the drawings:

30 Fig. 1 is a partial side elevation showing a scythe blade and the end portion of a scythe snath to which it is attached by means of a fitting embodying this invention.

35 Fig. 2 is an enlarged view of the same fitting but with the tool turned at right angles to the position in which it appears in Fig. 1, and with a fragment of the blade itself indicated in dotted outline.

40 Fig. 3 is a side view of the parts shown in Fig. 2, taken at a plane substantially at right angles to that of Fig. 2.

45 Fig. 4 is a transverse section taken as indicated at line 4—4 on Fig. 3.

Fig. 5 is a face view of the sleeve portion of the fitting with the adjustable saddle member removed.

50 Fig. 6 is a side elevation similar to Fig. 3, showing a modified construction to afford an additional adjustment.

Fig. 7 is a transverse section taken as indicated at line 7—7 on Fig. 6.

55 Fig. 8 is a section similar to Fig. 7, but showing the saddle tilted laterally by the additional adjusting means.

Fig. 9 is a side elevation similar to Fig. 3, showing another modification.

55 Fig. 1 shows a conventional scythe blade 1, hav-

ing the usual tapered tang 2 secured to a snath or handle 3 by means of a metallic fitting which includes a clamping ring 4, by which the tang 2 is bound against the fitting. In addition to the clamping ring 4, the fastening means embodying this invention comprises two main parts, namely, a sleeve member 5, which is secured fixedly over the end portion of the snath 3, and a saddle member 6 on which the tang 2 of the scythe blade is seated. For this purpose the saddle member includes a flat seating surface 7, which may be provided with a plurality of apertures 8 to receive the bent terminal 9 of the tang 2, these apertures 8 being variously located in the seating surface 7 to permit the blade 1 to be adjusted 10 to different angular positions with respect to the axis of the end portion of the snath 3.

The sleeve member 5 is fitted snugly over the end portion of the wooden snath 3, and may include an end wall or cap 10 which encloses the end grain of the snath and thus tends to preserve it against deterioration. The sleeve includes a pair of curved bearing surfaces 11, 11 which are preferably toothed or corrugated for inter-engagement with correspondingly shaped side 15 flanges 12, 12 of the saddle member 6. These inter-fitted curved contours of the saddle member and its bearings in the sleeve 5 permit the saddle to be shifted through a considerable angular range for varying the inclination of its seating 20 surface 7 with respect to the axis of the sleeve 5, so that the plane of the scythe blade 1 may be shifted with respect to this axis in accordance with the judgment or preference of the particular user. At any position in its range of adjustment 25 the saddle 6 is held fast by means of the clamping ring 4, which encompasses the sleeve 5, the saddle 6, and the tang 2 of the scythe blade in their assembled and adjusted relation. The ring 4 is shown provided with a pointed clamping screw 30 13, which impinges against the sleeve 5 at the side opposite the saddle 6 and, preferably, the sleeve is provided with one or more indentations 14 to receive the pointed end of the screw 13, so that it shall not slip along the sleeve under pressure. One limit of the angular range of the saddle 6 is indicated by the dotted outline of the blade at 1^a in Fig. 3, in which the plane of the blade is substantially parallel to the axis of the end portion of the snath and of the sleeve 5.

To accommodate the curved bearing portions 11 of the sleeve, the wood of the snath is cut away at both sides, leaving an upstanding middle portion 15, as seen in Fig. 4, but this middle portion also must be tapered toward the end of the 55

snath to provide for the angular range of movement of the saddle 6. Preferably, the end cap 10 is connected with the cylindrical portion of the sleeve by a strap 16, overlying the upstanding part 15 of the wood, as seen in Figs. 4 and 5. Thus the upper end portion 16^a of the strap 16 engages one end of the saddle 6 at one limit of its adjustment, and the opposite end 16^b acts as a stop to engage the saddle at the other limit 10 of its range.

It may be understood that the curved bearing surfaces 11 of the sleeve and the curved edges of the flanges 12 might be made smooth instead of toothed, but that the interlocking corrugations 15 are deemed preferable for maintaining the parts at the desired angle of adjustment. Or, if preferred, these contours could be made polygonal, with mutually engaging faces each constituting a short chord of the generally curved contour. 20 And it will also be evident that it is not essential that both the sleeve and the saddle have curved bearing elements; if one of these members is provided with a curved bearing surface, particularly a serrated surface, then the other member 25 need have only two or more tooth-like bearing points to engage the surface and to be shifted along it for adjusting the angle of the flat seating face to which the tang 2 is clamped.

It may also be recognized that the curved bearing surface of the sleeve may be either concave 30 or convex. Fig. 9 illustrates a design in which the sleeve 20 is provided with convexly rounded bearing surfaces 21, while the saddle 22 is formed with flanges 23, having concave bearing surfaces 35 24 supported on the convex bearings 21. This arrangement permits the clamping screw 25 of the clamp ring 26 to impinge against the sleeve 20 at a point approximately in the axis of the curved bearings 21, so that the ring 26 may lie 40 in a radial plane substantially throughout the range of angular adjustment of the saddle member 22. The snath 3^x is fitted tightly in the sleeve 20, and with this design it is not necessary to cut away quite so much of the wood of the 45 snath as for the structure shown in Figs. 1 to 5, since the bearing portions 21 may be formed on flat bosses substantially tangential with the outer surface of the sleeve 30, and it is only necessary to cut away a small portion of the snath to provide 50 clearance for the saddle in its inclined position in which it is illustrated in Fig. 9.

It is sometimes desirable to arrange for tilting the scythe blade in a direction transverse to that in which its angular inclination takes place, as 55 above described. As compared with a given position of the blade, such adjustment would have the effect of tilting it so as to raise or lower the tip or point of the blade with respect to the plane which it initially occupied. Figs. 6, 7 and 8 illustrate a construction for accomplishing such an 60 adjustment in addition to the adjustable inclination afforded by the structure of Figs. 1 to 5. For this supplemental adjustment there is no change in the design of the sleeve 5 with its ar- 65 cuate and serrated bearing surfaces 11, but the flanges 30 of the saddle member 31 are formed with threaded bosses 32, carrying adjustable set screws 33, whose points are positioned to engage in the serrations of the curved bearing surfaces 70 11. Thus, with two such bearing points 33 at each side of the saddle, it is effectively supported on the curved bearings 11, and may be shifted therealong by steps corresponding to the width of a single tooth or serration of the curved bearing. Then, for tilting the saddle and the 75

scythe blade which it carries, it is only necessary to adjust the set screws 33 at one side of the saddle so as to raise or lower that side with respect to its curved bearing track 11, as seen in Fig. 8.

The clamping ring 4 and its adjusting screw 13 must provide sufficient range for this tilting adjustment, and, since, preferably, the straight portion 4^a of the ring should bear flatly against the tang 2, the ring will be tilted or inclined, as indicated in Fig. 8; accordingly, the recess or indentation 14^a in the lower side of the sleeve 5 should extend circumferentially a few degrees in the sleeve, as also seen in Fig. 8. With this arrangement the initial positioning of the saddle member 31 is controlled by the upstanding middle portion 15 of the snath which results from cutting away portions of the latter to accommodate the serrated curved bearing tracks 11 and, if desired, additional guidance for the saddle may be provided by short upstanding flanges 11^a at the inner edges of the tracks 11. Thus the additional adjustment, permitting lateral tilting of the blade, is very simply accomplished, with a minimum of addition to the structure and with 25 very little extra expense of manufacture.

While there is shown and described herein certain specific structure embodying the invention, it will be manifest to those skilled in the art that various modifications and re-arrangements of the 30 parts may be made without departing from the spirit and scope of the invention, and that the same is not limited to the particular form herein shown and described, except in so far as indicated by the appended claims.

I claim:

1. A scythe snath fitting formed with bearing means, a seating member having an elongated seat to receive the tang of a scythe blade, said seat having a recess to receive the bent end of the tang and the seating member being provided with cooperating bearing means, one of said bearing means being of generally curved contour, the bearing means being shiftable one upon the other to vary the inclination of the tang and blade to the axis of the snath, and a single clamping means securing the seating member at adjusted position and securing the tang on the seating member.

2. A scythe snath fitting formed with bearing means, a seating member having a face formed to receive the tang of a scythe blade and provided with cooperating bearing means, one of said bearing means being of generally curved contour, the shifting of one bearing means upon the other operating to vary the inclination of the common plane of the tang and blade to the axis of the snath, said bearing means including inter-engaging projections and recesses to prevent one from slipping on the other, and clamping means holding said projections and recesses in engagement.

3. A scythe snath fitting comprising a sleeve secured to the end of the snath and having curved bearing surfaces at both sides, a saddle member formed with a seating face to seat the tang of a scythe blade and having flanges supported on said curved bearing surfaces of the sleeve whereby the saddle may be shifted on said curved bearings for adjustably inclining its seating face with respect to the axis of the sleeve, and clamping means securing the saddle in adjusted position on the curved bearing surfaces of the sleeve.

4. A scythe snath fitting comprising a sleeve secured to the end of the snath and having ar- 75

cuate bearing surfaces at both sides, a saddle member formed with a surface to seat the tang of a scythe blade and having flanges curved to fit upon said arcuate bearing surfaces respectively, whereby the saddle is inclinably adjustable with respect to the axis of the snath by shifting said flanges on their arcuate bearings, the bearings and flanges having inter-engaging serrations, and a clamp ring encompassing the sleeve, saddle and tang for binding them in adjusted position.

5. A scythe snath fitting comprising a sleeve secured to the end of the snath and having curved bearing surfaces at both sides, said bearings being formed with transverse serrations, a saddle member formed with a surface to seat the tang of the scythe blade with adjustable toothed members by which said saddle is supported on said curved serrated bearings, the shifting of said saddle on its curved bearings serving to adjustably incline its seating surface with respect to the axis of the sleeve, and the adjustment of said toothed members at one side of the saddle serving to tilt the saddle laterally and to correspondingly alter the relation of the scythe blade 15 to the snath, and clamping means formed to encompass said sleeve, saddle and tang for binding them in adjusted relation.

10

20

25

6. A scythe snath fitting formed with bearing means, a seating member having an elongated seat for the tang of a scythe blade, the seating member having bearing means cooperating with that of the fitting, one of said bearing means being of generally curved contour and the bearing means being shiftable one upon the other to vary the inclination of the tang and blade to the axis of the snath, means for also adjustably tilting the seating member laterally, and clamping means 10 formed to encompass the tang, the seating member and the snath for binding them together in adjusted relation.

7. A scythe snath fitting comprising a sleeve secured to the end of the snath and having convexly curved bearing surfaces at both sides, a saddle member formed with a seating face to seat the tang of the scythe blade and having cooperating bearing means supported on said convex bearing surfaces of the sleeve whereby the saddle 15 may be shifted on said curved bearings for adjustably inclining its seating face with respect to the axis of the sleeve, and clamping means securing the saddle in adjusted position on the convex bearing surfaces of the sleeve.
